(57) CLAIM

The ornamental design for a uniform, as shown and described.

DESCRIPTION

FIG. 1 is a front view of a uniform showing my new design; FIG. 2 is a rear view of the uniform; FIG. 3 is a right side view of the uniform; FIG. 4 is a left side view of the uniform; FIG. 5 is a top view of the uniform; FIG. 6 is a bottom view of the uniform; and, FIG. 7 is a top front side perspective view of the uniform. The broken lines on the waist of the uniform show stitching which forms no part of the claimed design. All additional broken lines show portions of the uniform which form no part of the claim.

1 Claim, 7 Drawing Sheets
